US0D1038128S

(12) **United States Design Patent** (10) **Patent No.:** **US D1,038,128 S**
(45) **Date of Patent:** **** Aug. 6, 2024**

(54) **KEYBOARD**

(71) Applicant: **Shenzhen Sqt Electronics Co., Ltd.**,
Shenzhen (CN)

(72) Inventor: **Ming Wu**, Shenzhen (CN)

(73) Assignee: **Shenzhen Sqt Electronics Co., Ltd.**,
Shenzhen (CN)

(**) Term: **15 Years**

(21) Appl. No.: **29/814,408**

(22) Filed: **Nov. 5, 2021**

(30) **Foreign Application Priority Data**

Oct. 8, 2021 (CN) 202130658644.0

(51) **LOC (14) Cl.** **14-02**

(52) **U.S. Cl.**

USPC **D14/391**

(58) **Field of Classification Search**

USPC D14/247, 320, 331, 333, 338, 346-347,
D14/387, 390-401, 406, 429, 455-456;
D18/1-2, 4.1-4.6, 7, 11, 12.2, 52;
D21/324, 409

CPC B41J 5/10; B41J 5/12; B41J 5/00; B41J
5/105; B41J 5/107

See application file for complete search history.

(57) **CLAIM**

The ornamental design for a keyboard, as shown and described.

DESCRIPTION

FIG. 1 is a perspective view of a keyboard showing my new design;

FIG. 2 is another perspective view thereof;

FIG. 3 is a front view thereof;

FIG. 4 is a back view thereof;

FIG. 5 is a top view thereof;

FIG. 6 is a bottom view thereof;

FIG. 7 is a left view thereof; and,

FIG. 8 is a right view thereof.

The broken lines shown in the drawings depict portions of the keyboard that form no part of the claimed design.

1 Claim, 8 Drawing Sheets
